Term of patent 3½ years

To all whom it may concern:

Be it known that I, Samuel Dunkelsberg, a citizen of the United States and a resident of the city of New York, in the county of Kings and State of New York, have invented a new, original, and ornamental Design for a Spectacle Front, of which the following is a specification, reference being had to the accompanying drawing, forming a part thereof.

Fig. 1 is a front elevational view of a spectacle front;

Fig. 2 is a top plan view of the same; and

Fig. 3 is the metal insert on an enlarged scale for the purpose of bringing out more clearly the ornamentation, showing my new design.

The ornamentation shown on the insert in Fig. 3 has been omitted from the insert in Figs. 1 and 2 for convenience of illustration.

The essential features of my design reside in the parts shown in full lines.

I claim:

The ornamental design for a spectacle front, as shown and described.
